CLAIM

The ornamental design for a temporomandibular joint prosthesis, substantially as shown and described.

DESCRIPTION

FIG. 1 is a perspective view of a temporomandibular joint prosthesis, showing my new design;

FIG. 2 is a left end elevational view thereof;

FIG. 3 is a right end elevational view thereof;

FIG. 4 is a top plan view thereof;

FIG. 5 is a side elevational view thereof;

FIG. 6 is a bottom plan view thereof;

FIG. 7 is an elevational view of the side opposite that shown in FIG. 5;

FIG. 8 is a perspective view of a second embodiment of a temporomandibular joint prosthesis;

FIG. 9 is a right end elevational view thereof;

FIG. 10 is a left end elevational view thereof;

FIG. 11 is a top plan view thereof;

FIG. 12 is a side elevational view thereof;

FIG. 13 is a bottom plan view thereof;

FIG. 14 is an elevational view of the side opposite that shown in FIG. 12.
